AMUSEMENT DEVICE

Glen D. Fleak, Beaumont, Tex., assignor of one-fourth to H. A. Mitchem, one-fourth to C. M. Lewis, both of Lake Charles, La., and one-fourth to W. D. Fleak, Chicago, Ill.

Application December 18, 1937, Serial No. 180,584

4 Claims. (Cl. 273—86)

The present invention relates to amusement devices or games, and has as its principal object to provide a device of this character where two or more players may compete with each other in a way that involves the speed and skill of operation by a player of a lever to produce movement of a visible object toward a goal that determines the winner by indicating the first object to arrive in an accurate and effective manner.

10 This invention is an improvement upon my Patent No. 1,965,140. In that patent, a plurality of figures may be caused to climb poles in response to the plays of two or more contestants. The present invention contemplates certain improvements over the device shown in that patent whereby the position of the contestants with respect to the figures may be somewhat remote without adversely affecting the play. In the present device novel driving means for causing

20 the climbing figures to move in response to accurate shots by the contestants are also provided. It is a purpose of the invention to provide, in a machine of the character described, means whereby, when two or more figures approach the

25 goal almost at the same time, extremely accurate means of indicating the winner may be employed. Other and more detailed objects and advantages will appear as the description proceeds in connection with the accompanying drawings 30 wherein a preferred form of the invention is shown. It is to be understood, however, that the drawings and description are illustrative only, and are not to be taken as limiting the invention, except insofar as it is limited by the claims.

35 In the drawings, Fig. 1 is a view in front elevation of a portion of the machine embodying the invention;

Fig. 2 is a sectional view on the line 2—2 of Fig. 1;

40 Fig. 3 is a sectional view taken on the line 3—3 of Fig. 2;

Fig. 4 is a fragmentary sectional view showing the details of the operating mechanism by which the contestant plays the game;

45 Fig. 5 is a rear view looking at the back of the machine shown in Fig. 1;

Fig. 6 is a plan sectional view taken on the line 6—6 of Fig. 5;

50 Fig. 7 is an end view looking toward the left hand end of the machine shown in Fig. 1;

Fig. 8 is a fragmentary plan view looking down on the mechanism shown in Fig. 2;

55 Fig. 9 is a plan sectional view taken on the line 9—9 of Fig. 5; and

Fig. 10 is a view in side elevation of the mechanism shown in Figs. 8 and 9.

Referring now to the drawings in detail, the present invention is embodied in a machine of the type commonly referred to as a carnival machine, in which provision is made for a plurality of contestants to engage in a game of skill. The machine embodies a plurality of climbing figures 10 which are caused to move up and down a plurality of vertical rods 11. As shown in the drawings, there are three of the climbing figures, although of course there may be as many as desired within practical limits, without changing the nature of the invention. Each figure is connected by its lower limbs 12 to a vertically movable plunger 13 slidably mounted in the rod 11. The upper limbs 14 of each figure are connected to a separately movable plunger 15, also slidable in the rod 11. The rods 11 are hollow, and on the sides opposite the players they are provided with vertically extending slots, as indicated at 16 in Fig. 2, the connection of the limbs of the figures being made through the slot 16 to the respective plungers. The lower plunger 13 is moved upwardly by means of cable or wire 17 which passes up through the upper plunger 15 over a pulley 18, then horizontally to the rear of the machine over a pulley 19, and downwardly to a winding member 20. The upper plunger 15 is moved by a second cable 21 which extends over similar pulleys 22 and 23 and is also connected to the winding member 20. The winding member 20 is so constructed and the cables 17 and 21 are so connected thereto, as shown best in Figs. 5 and 6, that upon actuation of the winding member 20 the lower plunger 13 is pulled up first and then remains stationary while the upper plunger 15 is pulled up the same distance. This causes the lower limbs of the figures to move upwardly first, and the upper limbs then move upwardly so as to simulate the natural climbing action of an animal.

The winding member 20 is provided with integral stub shafts 24 and 25 which are journaled in a frame 26. The cable 17 is threaded through an eye 27 in a lever 28 that passes through a bearing 29 formed on the winding member 20. The cable 17 is then secured at 30 to one cable receiving portion 31 of the winding member 20. The cable 21 is secured to another cable receiving portion 32 of the winding member 20, the portion 32 being directly opposite the portion 31 but offset axially of the member 20. The lever 28 is extended through a disk 33 that is integral with the stub shaft 24 and carries a stop pawl 34 which

is adapted to strike a shoulder 35 that is provided on the frame 26. A pin 36 on the disk 33 limits counter-clockwise movement of the lever 28 and the pawl 34. In the normal operation of pulling up the figures, the tension upon the cable 17 is sufficient to hold the lever 28 over into alignment with the member 31. In this position of the lever 28, the pawl 34 is drawn into the dotted line position shown in Fig. 7 so that it will clear the shoulder 35. This is also true on the downward movement of the figures as long as part of the cable 17 is wound around the portion 31. At the end of the downward movement of the figure, however, the cable 17 finally swings free of the portion 31 so as to move the lever 28 counter-clockwise with respect to the portion 31 through a very small angle. This movement takes place just before the figures reach their lower-most positions, and as a result, the pawl 34 swings out 20 against the stop 36 so as to be in position to engage the shoulder 35 and thus stop the figure at a different position. A light spring 28' connects lever 28 with disk 33.

Of course, on the winding up action which 25 raises the figures, the winding member turns in a counter-clockwise direction, as shown in Fig. 9, and starts the winding of the cable 17 upon the portion 31 immediately, thereby forcing the pawl 34 inwardly by drawing the lever 28 toward the portion 31.

The winding member 20 is driven by a friction disk combination embodying one disk 37 integral with the winding member, and a second disk 38 pivoted on the stub shaft 25. Both of these disks 35 have suitable coverings 39 of friction material adapted to engage a friction wheel 40 upon a drive shaft 41 which is driven by a motor 42. The disk 37 has a recess 43 in its periphery whereby, when the recess is opposite the friction wheel 40, 40 no driving force will be directly placed upon the disk 37. This disk, however, is provided with a plate 44 that rests against the disk 38 in order that the disk 38 may, by the frictional engagement between the plate 44 and the disk 38, start the disk 37 into rotation. A spring 45 presses the disk 38 against the plate 44.

Of course, the disk 37 and the winding member 20 would continue to rotate all the time while the shaft 41 is rotating if some means were not provided to prevent such rotation. This means is provided in the form of a lever 46 pivoted at 47 upon a suitable standard 48. The lever 46 has a stop portion 49 adapted to engage a projecting lip 50 on the portion 32 of the winding member 20. As shown best in Fig. 2, this stop portion is so located with respect to the recess 43 in the disk 37 that it stops the disk 37 with the recess 43 opposite the friction wheel 40 when the lip 50 comes against the stop 49. It is clear, of course, 55 that if the lever 46 is depressed out of the way of the lip 50, then the winding member will be rotated to wind up the cables 17 and 21 the amount measured by one complete rotation of the winding member 20. Of course, if the lever 46 were held 60 out of the way, the winding would continue steadily. The lever 46, however, is normally held in stop position by a spring 51 and is only released by lifting it against the pressure of the spring 51. This is accomplished by means of a link 52 and a 65 lever 53 which has a portion 54 projecting into a ball race 55 where it may be struck by a ball 56 entering the ball race 55 and falling downwardly.

The ball race 55 is a vertical channel between two semi-circular ball races 57 and 58. The ball 75 56 is propelled upwardly through the ball race

57 by a hammer 59 on the end of a lever 60. The lever 60 is held in retracted position by a spring 61 and can be advanced to hit the ball 56 by swinging it around its pivot 62 by means of a flexible Bowden wire member 63. The Bowden 10 wire leads to a thumb lever 64 that is mounted on a platform 65 in front of the figures and at any desired distance from the figures. The thumb lever 64 is enclosed in a shell 66 and carries a stop member 67 which may be adjusted to maintain the wire 63 free of slack. It will be obvious that if the thumb lever 64 is depressed quickly, it will swing the lever 60 in a clockwise direction and cause the hammer 59 to strike the ball 56. If the proper speed is imparted to the ball 56, it will 15 travel up the ball race 57 and drop into the vertical ball race 55 so as to strike the lever 54. If too much or too little force is applied to the ball 56 it will either go on into the ball race 58 or return back through the ball race 57. Thus a 20 contestant may exercise his skill and speed in manipulating the thumb lever 64 in endeavoring to cause the ball to enter the race 55. Each time the lever 54 is depressed by the ball 56 it releases the stop 49 on the lever 46 and permits the winding member 20 to complete one revolution. This will cause the figure to execute one climbing movement.

The operation of the motor 42 is controlled by a mercury switch 68 which is connected by suitable wiring (not shown) into the circuit of the motor 42, which is a reversible motor, so that when the switch is in the position shown in Fig. 7, for example, the motor will be caused to run in one direction to drive the winding member in 35 a clockwise direction, as shown in Fig. 2, and thus cause the figures to climb. When the switch 68 is tipped in the opposite direction, it reverses the motor and thus drives the friction wheel 40 in a direction to turn the winding member 20 40 in a counter-clockwise direction, as shown in Fig. 2, and thus lower the figures to starting position. The switch 68 is controlled by a link and lever arrangement which comprises a lever 69 fixed to the switch 68, a long link 70 having a 45 pivotal connection with the lever 69, a second link 71, and a lever 72 which is fixed to a shaft 73. The lever 72 is connected to a control link 73 by a lost motion connection provided by a slot 74 in the link 73 and a pin 75 on the lever 72. The link 73 connects to a hand lever 76 at its lower end. The function of the hand lever 76 is to effect a return of the lever 72 when this lever has been raised to the dotted line position shown in Fig. 7. Other functions of the lever 76 will be explained hereinafter.

The shaft 73 to which the lever 72 is fixed extends across the top of the machine in back of the hollow rods 11 and carries over each rod a permanent magnet 77 which is fixed to the shaft 73 so as to turn therewith. The shaft 73 also carries a weighted arm 78 which is of sufficient weight to turn the shaft 73 and lift the lever 72 with its associated links 71 and 70 to tilt the switch 68 into motor reversing position. Over each of the tubes 11 there is also provided an indicating plate 79 which is pivoted on the shaft 73 and has a portion underlying the magnet 77. The winner of the race between the figures is indicated by raising the plate 79 of 70 the winning figure in the following fashion:

Upon the upper plunger 15 there is provided a pin 80 which projects upwardly and is adapted to engage that part of the plate 79 which extends over the tube 11 as the plunger 15 is raised into 75

its uppermost position. The pin 80 first strikes the plate 79 and turns it upon the shaft 73 until the plate is brought into contact with the magnet 71. This magnet is of sufficient strength to hold the plate once it is brought into contact therewith, but is not strong enough to lift the plate when it is spaced below the magnet. After the plate 79 and the magnet 71 are brought together by the pin 80, the pin continues its vertical movement with the plunger 15 which, of course, turns the shaft 73 sufficiently to move the weight 78 over the vertical center line of the shaft 73; after which the weight 78 falls over into the position shown in dotted lines in Fig. 15, thereby causing the lever 72 to reverse the motor and move the indicating plate 79, which has been brought into contact with its magnet 71, into a vertical position. The reversal of the motor, of course, prevents any of the other figures from being advanced further, and therefore only the figure whose plunger 15 pushed its plate into contact with the associated magnet 71 will have the plate 79 raised.

In order that a plate 79 once stuck to the magnet, will not continue to be lifted each time the machine is operated, I provide means for separating the plate from its magnet before lowering the figures for a new contest. This is accomplished by means of a small shaft 81 which runs in front of the shaft 73 and which carries a series of wire loops 82, one loop in front of each of the plates 79. The shaft 81 has a lever 83 thereon which can be operated by a pull cord 84 to swing all of the loops 82 back toward the plates 79, and thus force any plate which is attached to its magnet away from the magnet so that it will fall into horizontal position.

It is necessary, in order that the contestants may all start at the same time, to control the balls 56 so that they will all be released for playing at one time. To accomplish this result, I provide a horizontally sliding bar 85 with a plurality of pins 86, one for each ball, which pins are located to extend into slots 87 provided in the back plate 88 of the ball race frame. The pins 86 are so located as shown best in Figs. 2 and 3 that if the bar 85 is moved to the right from the position shown in Fig. 3 it will move the ball 56 upwardly toward the ball race 51, out of the range of the hammer 59. The lever 76 has an arm 89 which is adapted to bear against a pivoted arm 90 that is pressed outwardly by a spring 91. The arm 90 is linked to a lever 92 which is fulcrumed on a post 93 and connected, at the end opposite to arm 90, to the bar 85 by a pin 94 sliding in a slot 95 in the bar 85. When the lever 76 is in the full line position shown in Fig. 1, it holds the arm 90 flat against the frame of the machine and thus pulls the bar 85 to the left, permitting the balls 56 to rest in playing position. Now, however, as the lever 76 is moved in a counterclockwise direction to the first dotted line position shown in Fig. 1, it first moves the arm 89 away sufficiently to permit the arm 90 to move out and force the bar 85 to the right, thus forcing all the balls up out of playing position. Further movement of the lever 76 into the second dotted line position shown in Fig. 1 pulls the link 73 down to bring the lever 72 into the full line position shown in Fig. 7, and to restore the weighted arm 78 to its active position shown in full line in Fig. 7. This, of course, results in the lever 72 setting the switch 68 in the position shown in Fig. 7, which is the driving position where the motor is caused to rotate in a

direction to cause the figures to climb if their respective winding members are connected to the drive shaft 41. The lever 76 in order to start play, must then be returned to the full line position shown in Fig. 1 where its arm 89 will force the arm 90 into the full line position shown in Fig. 1, thus retracting the bar 85 and releasing the balls 56 for play. The motor will continue to run and the figures will be caused to climb each time the ball associated therewith is made to pass through the ball race 55.

From the above description it is believed that the construction and operation of this device will be readily apparent to those skilled in the art.

Having thus described my invention, what I claim as new and desire to secure by Letters Patent is:

1. An amusement device having a plurality of upwardly extended guides, a figure operatively connected to each guide to be movable along the guide between a starting position and a goal, cable means for each figure for raising and lowering the figures along the guides, rotatable winding members for said cables, a common drive means frictionally connected individually with said winding members, stop means for each winding member operative to hold it against rotation in one direction only, manually actuated means individual to each stop means for releasing it, said drive means being reversible to turn said winding members in the other direction, and holding means individual to each winding member to prevent rotation thereof in said other direction, each of said cables being connected to the corresponding holding means to hold it in inoperative position until the cable is unwound from its winding member.

2. An amusement device having a plurality of upwardly extended guides, a figure operatively connected to each guide to be movable along the guide between a starting position and a goal, cable means for each figure for raising and lowering the figures along the guides, rotatable winding members for said cables, a common drive means frictionally connected individually with said winding members, stop means for each winding member operative to hold it against rotation in one direction only, manually actuated means individual to each stop means for releasing it, said drive means being reversible to turn said winding members in the other direction, and holding means individual to each winding member to prevent rotation thereof in said other direction, each of said cables being connected to the corresponding holding means to hold it in inoperative position until the cable is unwound from its winding member, said device having manual control means for reversing the drive means when said winding members are stopped by their respective holding means.

3. An amusement device having a plurality of upwardly extended guides, a figure operatively connected to each guide to be movable along the guide between a starting position and a goal, cable means for each figure for raising and lowering the figures along the guides, rotatable winding members for said cables, a common drive means frictionally connected individually with said winding members, stop means for each winding member operative to hold it against rotation in one direction only, manually actuated means individual to each stop means for releasing it, said drive means being reversible to turn said winding members in the other direction, and holding means individual to each winding member to prevent rotation thereof in said other direction, each of said cables being connected to the corresponding holding means to hold it in inoperative position until the cable is unwound from its winding member, said device having manual control means for reversing the drive means when said winding members are stopped by their respective holding means.

- member to prevent rotation thereof in said other direction, each of said cables being connected to the corresponding holding means to hold it in inoperative position until the cable is unwound from its winding member, said device having an individual indicator for each figure operable by the figure as it reaches goal, and means actuated by the first figure to reach goal, for reversing said drive means.
- 10 4. An amusement device having a plurality of figures mounted for movement in competition with each other to a goal, manually controlled means individual to each figure for imparting movement to said figures, indicating means at 15 the goal for each figure adapted when moved by

its associated figure to indicate that figure as the winner, means movable with each figure for initiating movement of its indicating means when it reaches the goal, and means common to all of the figures operable upon the initial movement by any one of said figures of its indicating means to raise that indicating means into winning position to the exclusion of the remaining indicating means, said means comprising a shaft, a magnet for each figure secured to the shaft, 10 the indicating means having metal therein which when the indicating means contacts the magnet will be attracted by the magnet and held thereto, and means to move said shaft.

GLEN D. FLEAK. 15
